2 Sheets-Sheet 2

UNITED STATES PATENT OFFICE

ROBERT C. MORTON, OF BALTIMORE, MARYLAND

GRATE BAR

Application filed May 29, 1930. Serial No. 457,125.

My invention relates to grate bars for furnaces and has for its principal object the provision of improved means whereby the fuel supporting bar thereof may, for the purpose of renewal, be easily and quickly disconnected from its supporting cradle.

A still further object of the invention is to provide improved means for supporting the grate bar in such a manner as to protect the cradle from the intense heat of the furnace.

A primary feature of the invention consists in providing the cradle with a plurality of laterally projecting arms adapted to underlie and support the fuel supporting bar, the latter being provided with depending portions arranged in interlocking relation with the arms.

Another feature of the invention consists in providing the fuel supporting member with depending plate-like portions adjacent the arms of the cradle, the plate-like portions being provided with laterally extending lugs or projections adapted to be disposed within grooves formed in the arms.

A further feature of the invention consists in providing the cradle with a plurality of laterally projecting arms which underlie and support the fuel supporting bar, one of the arms being provided with an aperture for receiving a portion depending from the bar and another of said arms being provided with a groove for receiving another portion depending from the bar.

Other and more specific features of the invention residing in advantageous forms, combinations and relations of parts will hereinafter appear and be pointed out in the claims.

In the drawings illustrating a preferred embodiment of the invention:

Fig. 1 is a plan view of the grate bar, portions of the fuel supporting bars being broken away.

Figure 2 is a side elevational view of the grate bar, portions of the fuel supporting bars being broken away.

Figure 3 is an enlarged sectional view taken on line 3-3, Figure 2.

Figure 4 is a fragmentary sectional view taken on line 4-4, Figure 3.

Figure 5 is an enlarged sectional view taken on line 5-5, Figure 2.

Figure 6 is a fragmentary sectional view taken on line 6-6, Figure 5.

Figure 7 is an end view of the grate bar as viewed from the left of Figure 1.

Figure 8 is a detailed view of the means employed for connecting the fuel supporting bar and cradle.

Referring more particularly to the drawings 1 indicates the cradle and 2 the fuel supporting bars. Adjacent its ends the cradle is formed with socket portions 3 and 4 adapted to receive pins or trunnions (not shown) by which the cradle is supported in the furnace. The bottom portion of the socket 4 is preferably open so that it may be dowered or dropped upon its associated supporting trunnion and the side walls of the socket are preferably formed with aligned apertures 5 for receiving a pin or the like (not shown) adapted to extend beneath the trunnion. The sockets 3 and 4 are integrally connected by a body portion 7 which may advantageously be in the form of a substantially vertical bar.

Intermediate its ends the cradle is formed with a plurality of pairs of laterally projecting arms 8, 9 and 10, respectively. The arms 8 and 9 are respectively disposed adjacent to but inwardly of the sockets 3 and 4 while the arms 10 are disposed adjacent the central portion of the cradle substantially midway between the arms 8 and 9. The inner face of each of the arms 8 and 9 is fashioned with a groove or recess 11. The grooves formed in the arms of each pair diverge downwardly and the side walls 12 and 13 of each groove diverge downwardly with respect to each other.

The central arms 10 are formed by spaced plate-like or wall portions 14 connected at their outer ends by a wall 15. These wall portions, together with the adjacent part of the portion 7 of the cradle, define apertures or openings 16.

Resting upon and supported by the laterally projecting arms of the cradle are the

fuel supporting bars 2 which preferably extend continuously from one end of the cradle to the other. Although the bars have been shown with a plurality of longitudinally extending air passages or openings it will be appreciated that these passages may be of any desired size or configuration. At their ends the bars 2 are suitably shaped or cut away to pass around the adjoining portions 5 of the sockets 3 and 4, the upper surfaces of which are disposed above the arms of the cradle in substantially the same plane as the top surfaces of the grate bars. Each grate bar is integrally formed with a plurality 10 of depending plate-like members or portions 17 respectively disposed adjacent the arms 8 and 9 of the cradle. Each of the plate-like portions may advantageously be of triangular shape and each is formed with an 15 outwardly and laterally extending lug or projection 18 adapted to be disposed within the groove of the adjacent arm. These lugs incline downwardly and outwardly and they are preferably wider at their upper portions 20 than at their lower portions. The bars 2 are also formed substantially midway of their ends with depending plate-like portions 19 adapted to extend into the apertures 16 in the central arms 10. These plate-like portions 25 may also be substantially triangular in shape. The side walls 14 of the arms 10 and the plate portions 19 are formed with registering apertures to receive pins 20 for detachably connecting the cradle and grate 30 bars. These pins before being inserted in the openings are of angle shape as illustrated in Figure 8. After being inserted in the openings the projecting end of the pin is bent upwardly and overlaps the adjoining 35 wall of the arm 10 in the manner shown in Figure 6. In order that the pin may be readily removed when it is desired to renew the bar the downwardly projecting end of the pin extends below the adjacent portion 40 of the side wall of the arm so that it may be struck by a hammer or the like and bent upwardly into a substantially horizontal position. The pin may then be driven from the 45 openings in the same direction in which it was inserted.

Due to the fact that the lugs 18 of one of the bars 2 and the grooves of the adjacent arms respectively diverge downwardly with respect to the lugs of the other bar and the 50 grooves in its cooperating arms it will be appreciated that to remove one of the bars from the cradle for the purpose of replacement it will have to be moved upwardly in an inclined direction toward the remaining bar. However, sufficient clearance intervenes between the two bars so that one will not interfere with the removal or replacement of the other. It will be perceived that since the upper portion of each lug is wider than its lower portion 55 and since the groove with which it coop-

erates is also wider at the top than at the bottom the lugs may be readily inserted in the grooves without carefully aligning the parts and yet when the bar is assembled with the cradle very little clearance intervenes between the upper portion of each groove and its associated lug.

70

As all portions of the cradle, together with the parts of the fuel supporting bars which interlock therewith, are disposed beneath the main body portions of the bars, the cradle, with the exception of its sockets, is protected from the intense heat within the furnace. Thus the possibility of warping of the cradle and the portions of the bars cooperating therewith is greatly reduced. Furthermore, since the fuel supporting bars rest upon and are supported intermediate their ends by the arms of the cradle they are prevented from warping downwardly to any appreciable extent.

75

80

85

90

95

Although the cradle has been illustrated as being provided with three pairs of arms a greater or less number may be employed depending upon the length of the fuel supporting bars supported thereupon. Other modifications and changes may be made in structural details of the grate bars and cradle without departing from the spirit of the invention as defined by the following claims.

100

I claim:

1. A furnace grate involving a cradle having a plurality of arms projecting laterally thereof intermediate its ends, and a fuel supporting bar extending longitudinally of said cradle and overlying and supported by said arms, said bar having a plurality of depending members respectively disposed adjacent said arms, the adjacent members and arms having tongue and groove connection.

105

2. A furnace grate involving a cradle having a body portion and a plurality of arms projecting laterally from the latter intermediate its ends, each of said arms being provided with a groove, and a fuel supporting bar overlying and supported by said arms, said bar extending longitudinally of the cradle and having depending members respectively disposed adjacent said arms, each of said members having a portion disposed within the groove of the adjacent arm.

110

3. A furnace grate involving a cradle having a plurality of arms projecting laterally thereof intermediate its ends, each of said arms being provided with a groove, and a fuel supporting bar overlying and supported by said arms, said bar having downwardly extending plate-like portions respectively overlapping said arms, each of said plate-like portions being provided with a lug disposed within the groove of the adjacent arm.

115

4. A furnace grate involving a cradle having a plurality of arms projecting laterally thereof intermediate its ends, the adjacent sides of said arms being respectively provided

120

125

130

with grooves, and a fuel supporting bar extending longitudinally of the cradle and overlying and supported by said arms, said bar having a plurality of depending plate-like portions respectively disposed adjacent said arms, each of said portions being provided with an outwardly extending lug disposed within the groove of the adjacent arm.

5. A furnace grate involving a cradle having a body portion and a plurality of arms projecting laterally of the latter intermediate its ends, and a fuel supporting bar overlying and supported by said arms, said bar extending substantially parallel with said

10 body portion and having a plurality of depending plate-like members respectively provided with laterally extending lugs adjacent said arms, each of said arms having portions embracing the lug of the associated plate-

15 like member of the bar.

6. A furnace grate involving a cradle having a plurality of arms projecting laterally thereof intermediate its ends, and a fuel supporting bar overlying and supported by said arms, said bar being provided with a plurality of depending members respectively adjacent said arms, one of said arms being provided with an aperture for receiving one of said depending members and another of said

20 arms being provided with a groove for receiving another of said depending members, said apertured arm and the associated depending member being provided with registering apertures to receive means for detachably connecting said bar and cradle.

7. A furnace grate involving a cradle having a plurality of laterally projecting arms, and a fuel supporting bar overlying and supported by said arms, one of said arms comprising spaced wall portions integrally connected adjacent their outer ends, said bar having a depending member interposed between the said spaced wall portions, said member and wall portions being provided

25 with registering apertures for receiving means for detachably connecting the bar and cradle.

8. A furnace grate involving a cradle having a plurality of pairs of laterally projecting arms, the arms of each pair being provided with downwardly diverging grooves, and a plurality of fuel supporting bars respectively overlying and supported by one arm of each pair, said bars having depending members respectively disposed adjacent the arms of the cradle, each of said members having a portion disposed within the groove of the adjacent arm.

9. A furnace grate involving a cradle having a plurality of pairs of laterally projecting arms, and a plurality of fuel supporting bars respectively overlying and supported by one arm of each pair, each of said bars being provided with a plurality of depending members respectively disposed adjacent the asso-

ciated arms, the depending members of one bar diverging downwardly with respect to the corresponding members of the other bar and each of said arms having portions embracing the adjacent depending member.

70

10. A furnace grate involving a cradle having a body portion and a plurality of arms projecting laterally of the latter, and a fuel supporting bar extending longitudinally of said body portion and overlying and supported by said arms, said arms being disposed intermediate the ends of said bar and having portions disposed in interlocking relation therewith.

75

11. A furnace grate involving a cradle having a plurality of pairs of laterally projecting arms, the arms of each pair extending in opposite directions, and a plurality of fuel supporting bars, each bar resting upon and being supported by one arm of each of said pairs, said arms being disposed intermediate the ends of the bars and having portions disposed in interlocking relation therewith.

80

In testimony whereof I affix my signature.
